FRANK W. STEERE, OF HIGHLAND PARK, MICHIGAN, ASSIGNOR, BY MESNE ASSIGNMENTS, TO SEMET-SOLVAY ENGINEERING CORPORATION, OF NEW YORK, N. Y., A CORPORATION OF NEW YORK

GAS MANUFACTURE

Application filed September 23, 1924. Serial No. 739,289.

This invention relates to water gas manufacture and more particularly to water gas sets adapted to practice the back-run process and in which the steam required for the back-run is produced by introducing water at a suitable point in the plant and utilizing the heat content of the plant to convert it into steam.

According to the present invention the water is introduced into the apparatus in such a way that contact thereof with the walls or lining of the apparatus is prevented, i. e., substantially all of the water is converted into steam before it can come in contact with the apparatus of the plant. For this purpose a device is used for introducing the water into the plant, preferably the superheater, which is so constructed and positioned that the water is introduced at the top of the superheater relatively distant from the lining thereof and in a finely divided condition preferably as a mist or fog, the net result being that substantially no deposition or contact of water as such on the lining takes place. In this way the disintegration and pulverization which tends to result from contact of water with the highly heated lining is avoided, at the same time the heat content of the apparatus is efficiently utilized for the production of the desired high temperature steam, and only the top of the superheater is subjected to any appreciable cooling effects.

One object of my invention is to cheapen the production of water gas manufacture by providing a water spray properly constructed and positioned within the superheater of the gas plant so as to do away with the necessity for the introduction of steam into the superheater. Another object is to provide means for permitting the quick and simple removal of the water spray from the superheater when it is desired to close the plant.

With the above, and other objects, in view, my invention consists in the arrangement, combination and construction of the various parts of my improved device as described in the specification, claimed in my claims and shown in the accompanying drawings, in which:

Fig. 1 is a side elevation of a gas plant in which my invention is employed.

Fig. 2 is a sectional view partly in elevation taken on line 2—2 of Fig. 1.

Fig. 3 is a detail view in vertical section of the spray utilized in my invention.

I have shown the conventional carburetted water gas plant, consisting of a generator 5, a carburetor 6, a superheater 7 and a wash box 8. An air blast pipe 9 is connected through the pipe 10 with the bottom of the generator and a quick shut-off valve 11 is utilized for closing the blasting line when the blasting operation is completed. Steam may then be furnished from a suitable source of supply through the passages 12, 13 and 10 into the bottom of the generator for making the customary "up run" of gas.

The customary connections such as the passage 14 from the generator to the carburetor, the passage 15 from the carburetor to the superheater and the passage 16 from the superheater to the wash box are used. Likewise the customary stack cap 17 is employed.

When it is desired to make the so-called "back-run" instead of introducing steam into the top of the superheater through the passage 16 or otherwise, I introduce a flow of water such as is illustrated in Fig. 2, through the spray 18.

In mounting the spray within the superheater, I utilize a housing or nozzle 19 which may be welded to the metal casing of the superheater as at 20. The water connection 21 leading to the spray 18 passes through this housing 19 and the stuffing box 40, and is connected at its outer end to a hose, or other flexible connection, not shown, so that the spray 18 may be withdrawn from the superheater. The stuffing box 40 is provided with a flange 41 which is bolted by bolts 42 to the movable flange 43 on the housing 19, the flange 44 on the end of the housing being positioned between the flanges 41 and 43.

Water is drawn by means of a pump 23 from any suitable source of supply, is passed into a pressure tank 24 and thence through the pipe 25, a strainer 26, suitable piping 27, and either through the piping 45 or the piping 22, into the spray. Along the piping 27

are provided a pressure gauge 28, a water meter 29 and a quick-shut-off valve 30. The passage of the water through the piping 45, carries it through coils 46 disposed around the superheater offtake 16, with the result that the water is preheated during the up-run operation, so that less heat and time are required to convert it into steam for use during the back-run operation. The coils 46 should 10 be of sufficient capacity to hold an ample water supply for the back-run cycle inasmuch as no appreciable heat is passed into the off-take 16 during the back-run.

I have provided valves 47, 48 and 49, so that 15 when water is passed through the coils 46, the valve 49 may be closed and the other two opened, while when the water is passed directly into the spray, without preheating, the valves 47 and 48 may be closed and the valve 20 49 opened.

When it is desired to close the plant so that no more water is supplied in the top of the superheater, the spray 18 is drawn out into the housing or nozzle 19 so as to be completely removed from the superheater. 25

It will be noted that the face of the spray 18 is in effect corrugated, as shown in Fig. 3, and the spray openings 31 are positioned in the angled sides of the corrugations so as to 30 cause the fine streams of water to cross each other and tend to break into a fine spray or fog. The very small openings in the spray itself will also assist in bringing about this result.

35 With an arrangement such as above described, the fine spray of water will be immediately vaporized by the intense heat present in the superheater so that the steam will have been generated before the water can 40 strike the sides or walls of the superheater, thus preventing disintegration of the superheater walls.

It is obvious that various changes may be made in the arrangement, combination and 45 construction of the various parts of my improved device without departing from the spirit of my invention, and it is my intention to cover by my claims such changes as may be reasonably included within the scope thereof. 50

What I claim is:

1. A water gas plant comprising a single generator, a single carburetor, a single superheater and wash box connected in series, a 55 passage leading from the base of the generator to the wash box, an upwardly directed spray nozzle positioned within the superheater at substantially the top thereof, said nozzle having a pipe connection extending 60 through the superheater wall, whereby said nozzle is positioned away from said superheated wall, and means for supplying water to said spray nozzle through said pipe connection, said water being generated into 65 steam at substantially the top of said super-

heater for use during the back-run combustible gas-making cycle.

2. A water gas plant comprising a generator, carburetor, superheater and wash box connected in series, a passage leading from the base of the generator to the wash box, a housing on said superheater at substantially the top thereof, a pipe extending through said housing arranged to be slidably moved therein, a spray nozzle on the end of the pipe extending into the superheater, means for supplying water to said nozzle, said nozzle being positioned away from the superheater walls and directed to feed said water upwards, whereby contact of said water with the superheater walls is substantially prevented and the water is generated into steam for use during the back-run combustible gas-making cycle.
